UNITED STATES PATENT OFFICE

VAHAN HAGOPIAN, OF NEW YORK, N. Y., ASSIGNOR TO A. S. BECK SHOE CORPORATION, OF NEW YORK, N. Y., A CORPORATION OF NEW YORK

DESIGN FOR A STORE FRONT

Application filed March 13, 1930. Serial No. 34,842. Term of patent 14 years.

To all whom it may concern:

Be it known that I, VAHAN HAGOPIAN, a citizen of the United States, and a resident of the city of New York, in the county of New York and State of New York, have invented the new, original, and ornamental Design for a Store Front, of which the following is a specification.

Reference is had to the accompanying drawing, forming part thereof, wherein

I claim:

The ornamental design for a store front substantially as shown and described.

VAHAN HAGOPIAN.
